(57) **CLAIM**

The ornamental design for a watercraft deck seating, as shown and described.

DESCRIPTION

FIG. 1 is a perspective view of a watercraft deck seating, showing my new design;

FIG. 2 is an enlarged front elevation view thereof;

FIG. 3 is an enlarged rear elevation view thereof;

FIG. 4 is a side elevation view thereof, the opposite side being a mirror image thereof;

FIG. 5 is a top plan view thereof; and,

FIG. 6 is a bottom plan view thereof.

The broken lines shown are included for the purpose of illustrating the unclaimed portions of the article and form no part of the claimed design.
